UNITED STATES PATENT OFFICE.

HERBERT J. SAUVAGE, OF CHICAGO, ILLINOIS, ASSIGNOR, BY MESNE ASSIGNMENTS, TO THE TRUSTEES OF ELECTRO THERMOSTATIC CONTROL COMPANY, OF CHICAGO, ILLINOIS, A TRUST ESTATE.

THERMOSTATIC APPLIANCE.

Application filed July 5, 1924. Serial No. 724,278.

My invention concerns improvements in appliances sensitive to temperature changes and which are constructed to operate electrical or mechanical devices within certain ranges of temperature fluctuations.

One object of the present invention is to provide a structure of this character of the expandible and contractible bellows or accordion type or style which will operate with great accuracy and exactitude and within substantially narrower ranges of temperature change than similar appliances.

Another purpose of the invention is to supply a construction of this form which has no bearings directly or indirectly associated with the bellows device and hence the appliance includes no structure requiring oiling or which would be likely to collect dust and dirt by reason of the presence of a lubricant, such fouling being detrimental to the effective and efficient operation of the structure.

A further aim of the invention resides in the production of a thermostatic appliance of this general character in which the two end walls of the bellows are always maintained substantially true or in parallelism without the employment of bearings for guiding elements.

So far as I am advised, it has been necessary heretofore to use some form or style of sliding bearing or its equivalent to prevent the movable end wall of the bellows from becoming tilted or tipped out of its proper position.

My new device overcomes the employment of such a bearing and at the same time the appliance is rendered more satisfactory and reliable in the performance of its functions.

To enable those skilled in this art to have a full and complete understanding of the invention and its various structural and functional advantages, in the accompanying drawing forming a part of this specification, and throughout the views of which like reference characters relate to the same parts, I have illustrated a desirable and preferred embodiment of this invention.

In this drawing:

Figure 1 is an elevation of the thermostatic appliance with the cover removed; and

Figure 2 is a vertical central cross-section of the device on line 2—2 of Figure 1, the

parts being viewed in the direction indicated by the arrows.

Referring to this drawing, it will be perceived that the improved and novel structure includes a supporting or back plate 10 of appropriate shape adapted to be fastened in any approved manner, not shown, on a wall.

Such member 10 has two, outstanding, horizontal, flat lugs or ledges 11 and 12 projecting forwardly from its front face.

The round or circular lower or end wall member 13 of the bellows or accordion shaped unit 16, internally supplied with a fluid quickly and actively sensitive to temperature variations, such as ether, or a mixture of ether and alcohol, has a threaded boss 14 on its under face screwed into a threaded hole 15 in the projection 11, whereby such lower or bottom wall of the thermostatic device is fixedly maintained in a definite plane, usually horizontal.

The top wall or round plate 17 of the temperature-sensitive plaited or corrugated extensible and reducible metal member 16 has a central depression 18, the face of which is a flat round surface.

Internally this hollow, fluid-charged unit has a longitudinally-disposed tube 19 fixed to the bottom wall 13 with its upper end near the under face of the top wall 17, such hollow member acting as a stop or abutment to limit or restrict the descent of such top wall under the contracting action of the bellows.

A substantially-rectangular, upright yoke or frame 20 fits around or encloses the member 16 and the under face of its top horizontal wall has a cylindrical, flat-surfaced boss received in the recess 18 and bearing directly on the top wall of the bellows in such depression.

At its top, this yoke has an upward extension 22 fitted with an upper, flat, horizontal, bearing surface 23.

The bottom cross wall of the yoke or frame has a pair of shallow, upstanding, spaced lugs with top, flat, horizontal surfaces in the same plane or in register. These by bearing on the under face of the ledge 11 limit the upward expansion of the bellows and under those conditions they maintain the top wall of the bellows through the lug 21 from becoming tilted or inclined.

out of its proper plane parallel to the wall 13 and the surfaces 24, 24.

A coil contractile spring 25 has a loop or eye 26 at its upper end taking through a bevelled or doubly tapered aperture 27 in the lower cross-wall of the yoke.

The other or opposite end of the spring encircles and is secured to a nut 28, the threaded aperture of which accommodates a vertical, screw-threaded shaft or rod 29, a reduced-diameter, cylindrical part 30 of which is revoluble in a bearing 31 in the lower ledge 12, the bottom protruding end portion of the section 30 being equipped with a turning handle or disc 32 pinned thereon at 33.

To prevent the nut from turning with the rotation of the shaft, and hence causing the movement or travel of the nut longitudinally of the shaft, the nut has a lateral, bifurcated extension 34 straddling and cooperating with an upright, stationary rod 35 mounted in aligned holes in the two ledges.

At the top of the back or supporting plate 25 a suitably-shaped sheet-metal cradle or saddle 36 is hinged or pivoted off-center on an outstanding pin or shaft 37 carried by or mounted on the member 10 and such saddle or cradle on its under surface has a lug 38 bearing on the face 23 of the yoke.

This cradle clamps around a hollow glass body 39 containing a small quantity of mercury 40, which, under the rocking action of the hinged body makes and breaks electrical contact with a pair of terminals 41 and 42 located inside the glass shell and connected to wires 42 and 43 extending out backwards through the plate 10 from which they are suitably insulated by proper bushings 44 and 45.

Owing to the flat, substantial bearing of the part 21 on the center of the upper face of the top wall of the bellows and the downward pull of the spring on the yoke along the axis line of the bellows, and because of the fact that the bottom wall of the bellows is fixed and immovable, the force exerted by the spring holds the bellows top wall in proper position under all circumstances precluding its becoming canted or tipped out of its correct horizontal relation.

This condition prevails throughout the range of movement of such top wall, but when the surfaces 24, 24 strike against the under face of ledge 11, thus limiting the upward expansion of the bellows, the spring is no longer active and these cooperating surfaces then hold the wall in correct and proper position compensating under these conditions for the absence of the action of the spring.

The spring tension may, of course, be varied or adjusted by turning the screw-shaft by means of its handle or hand-wheel 32.

Inasmuch as the glass body 39 and its mounting are hinged to one side of their center of gravity, they tend to rock down to the position shown in Figure 1 wherein the mercury closes the electrical circuit between the pair of enclosed terminals. 70

Such circuit will remain closed until the bellows expands under heat action and rocks the glass body and its mounting around the hinge causing the mercury to flow down 75 hill away from and breaking the circuit at such terminals.

As the top wall of the bellows descends under cooling action or contraction, the electric-switch is permitted to swing down 80 again into circuit-closing relation.

It is to be observed that the movable end wall of the bellows is always kept parallel to its bottom wall and this is accomplished solely by the central pull of the spring 85 and without the employment of any guiding bearings comprising relatively slidable elements necessitating lubrication and hence likely to become fouled with adhering dust and dirt. 90

It should be noted that the single spring, by reason of its action on the yoke equipped with the member 21 bearing on the top wall of the bellows throughout a substantial area keeps such top wall from tilting or becoming tipped in any direction whatsoever and this restricting influence is not limited to the plane of the yoke but is just as active in all other vertical planes. 95

Whereas in this application the new device has been shown and described in co-operative relation with an electric switch, it is to be understood that it could just as readily coact with some mechanical device designed to be operated upon changes of 105 temperature.

Many minor mechanical changes may be made in the device presented without departure from the substance and essence of the invention and without the sacrifice of 110 any of its substantial benefits and advantages or stated somewhat differently the invention is susceptible of a variety of embodiments all falling within the scope of the appended claims, by which the invention is defined. 115

Suitable stops, not fully shown in the drawing, may be used if desired to limit the rocking movements of the mercury-equipped glass body in both directions. 120

I claim:

1. In a thermostatic appliance of the character described, the combination of an expansible and contractile thermostatic bellows, a supporting ledge to which one end wall of said bellows is fixedly secured, said ledge having a surface parallel to the plane of said bellows end wall, a yoke around said bellows bearing on the outer face of the opposite end wall of said bellows, 125 130

a coil contractile spring secured to the yoke on the opposite side of said ledge from said bellows, and means to adjust the tension of said spring, said yoke under certain conditions being adapted to bear on said ledge surface and to maintain said movable bellows end wall parallel to said fixed bellows end wall.

2. In a thermostatic appliance of the character described, the combination of an expansible and contractible thermostatic bellows, a supporting ledge to which one end wall of said bellows is fixedly secured, a yoke around said bellows bearing on the outer face of the opposite end wall of said bellows, and a coil contractile spring secured to the yoke on the opposite side of said ledge from the bellows and acting through the yoke to maintain the movable end wall of said bellows substantially parallel to the fixed wall thereof throughout the range of movement of said movable end wall.

3. In a thermostatic appliance of the character described, the combination of an expansible and contractible thermostatic bellows, a supporting ledge to which one end wall of said bellows is fixedly secured, a yoke around said bellows bearing on the outer face of the opposite movable end wall of said bellows, and a coil contractile spring secured to the yoke on the opposite side of said ledge from the bellows and on the axis line of the latter, whereby said spring through the yoke tends to maintain said bellows end walls in substantial parallelism.

4. In a thermostatic appliance of the character described, the combination of an expansible and contractible thermostatic bellows, a supporting ledge to which one end

wall of said bellows is fixedly secured, a yoke around said bellows bearing on the outer face of the opposite movable end wall of said bellows, a coil contractile spring secured to the yoke on the opposite side of said ledge from the bellows and substantially on the axis line of the latter, whereby said spring through the yoke maintains said bellows end walls in substantial parallelism, and means to adjust the tension of said spring.

5. In a thermostatic appliance of the character described, the combination of an expansible and contractible thermostatic bellows, means fixedly holding one of the end walls of said bellows, a first substantially frictionless means constituting the sole means tending to maintain the opposite movable end wall of said bellows substantially parallel to said fixed end wall throughout the range of travel of such wall, and a separate second means to keep said movable end wall in such parallelism when said first means is inoperative to effect such parallelism.

6. In a thermostatic appliance of the character described, the combination of an expansible and contractible thermostatic bellows, means to hold an end wall of said bellows in fixed position, and substantially frictionless means including an expanded spring tending to contract acting directly on the outer face of the opposite movable end wall of said bellows to prevent it from tilting throughout its range of travel.

In witness whereof I have hereunto set my hand.

HERBERT J. SAUVAGE.
